UNITED STATES PATENT OFFICE.

WALLACE M. CUTLER, OF FREEPORT, NEW YORK, ASSIGNOR TO THE BOX CAR FLUSH DOOR COMPANY, OF NEW YORK, N. Y., A CORPORATION OF NEW YORK.

MEANS FOR OPERATING CAR-DOORS.

1,117,798.

Specification of Letters Patent.

Patented Nov. 17, 1914.

Application filed November 1, 1913. Serial No. 798,735.

To all whom it may concern:

Be it known that I, WALLACE M. CUTLER, a citizen of the United States, residing at Freeport, in the county of Nassau and State of New York, have invented certain new and useful Improvements in Means for Operating Car-Doors; and I do hereby declare the following to be a full, clear, and exact description of the invention, such as will enable others skilled in the art to which it appertains to make and use the same.

This invention relates to means for operating doors, and has for its object to produce an apparatus especially adapted for operating car doors, which will be simple in construction, comparatively inexpensive to manufacture and more efficient in action than those heretofore proposed.

With these and other objects in view, the invention consists in the novel details of construction and combinations of parts more fully hereinafter disclosed and particularly pointed out in the claims.

Referring to the accompanying drawings forming a part of this specification in which like numerals designate like parts in all the views:—Figure 1 is a side elevational view of a car and door with my invention applied thereto; Fig. 2 is a sectional view taken on the line 2—2 of Fig. 1; Fig. 3 is a view similar to Fig. 1, but showing the door in its partially open position; Fig. 4 is a sectional view taken on the line 4—4 of Fig. 3; Fig. 5 is a side elevational view of a slightly modified form of the operating portion of my invention; Fig. 6 is a side elevational view of a further slightly modified form of the operating portion of my invention; Fig. 7 is a detail elevation view of a roller and housing or a casting co-operating therewith; Fig. 8 is an end elevational view partially in section of the parts shown in Fig. 7; and, Fig. 9 is an end elevational view partially in section of the operating portion of my invention.

1 indicates any suitable vehicle, such as a railroad car; 2, a door; 3, a top rail or guide for the door 2; 4, a bottom rail or support for said door; 5, stops carried by the car body to limit the sliding movement of the door 2; 6, supports for the rail 4; and 7, combined guides and stops for the door 2

mounted on the car body near the edge of the opening for said door.

I preferably provide spring controlled 55 guides 8 adapted to contact with the upper rail 3, which guides are mounted on the upper ends of the vertical rods or supports 9 and 10 for the door. The lower end 27 of the rod 9 is mounted for oscillation in a 60 casting 26 carrying a roller 11. The said roller is adapted to rest upon and travel along the upper edge of the supporting rail 4.

Rigidly secured near the upper end of the 65 rod 9 is the hinge lever member 13 through the end of which passes the hinge pin 14 carried by the countersunk casting 15 mounted near one edge of the door 2, as will be clear from Figs. 1 and 2. Likewise, near the upper end of the rod 10 is the lever-like hinge member 16 rigidly secured to said rod 10 at one end, and rotatably secured to the pin 17 carried by the countersunk casting 18 mounted on the other 70 edge of the door 2. In the same way, rigidly secured near the lower end of the rod 9 is the hinge member 20 associated with the hinge pin 21 carried by the casting 22; and near the lower end of the rod 10 is the similar hinge member 23 rigid with said rod and associated with the hinge pin 24 carried by the casting 25 mounted on the door. In like manner, located below the hinge member 23 is the casting 28 carrying the 85 roller 12 and the lower end of the rod 10 is fitted to oscillate in said casting 28. 29 represents metal guards secured near the edge of the door 2 in order to prevent injury to said door when it contacts with the stops 90 5. In like manner, the guard 30 located near the opposite edge of the door 2 protects the said edge when it contacts with the upper guide and stop 7, while that portion 31 of the casting 22 likewise protects the said door 95 when it contacts with the lower stop 7.

Rigid with the casting 28 is the extension 32 forming a slot 33, and in this slot, the pivot pin 34 is adapted to reciprocate. The said pin 34 is carried by an L-shaped lever 100 having a handle portion 35 and an operating portion 36, the lower end of which, as seen in Fig. 3, carries the pin 37. The said pin 37 passes through the connecting rod 38,

which in turn passes through a guide 40 carried by the casting 28. The other end of the rod 38 passes through a similar guide 41 on the casting 26, and is secured therein by means of the pin 42 which passes through said rod 38, as well as through the supporting roller 11, as will be clear from Fig. 9 of the drawings. The lever 35 being pivoted by the pin 37 to the rod 38, and the pin 34 also passing through said lever, it is evident that as the said lever is turned in a clockwise direction as seen in Fig. 1 on the pin 34 as a center, the said pin will ride up in the slot 33 from the position shown in Fig. 1 to the position shown in Fig. 3. If the casting 28 were fixed, the result of this motion would tend to force the rod 38 bodily to the left as seen in Fig. 1, and should the casting 28 still be held fixed, the casting 26 and rod 9 would tend to move along the rail 4 toward the left and thereby move the pin 14 and the edge of the door outwardly from the wall of the car. The support 9 and casting 26 will, under such circumstances, move along the rail 4, because the lower end of the casting 26 is provided with guides 65 and 66, Fig. 9, which straddle said rail 4 and because the rod 38 is rigidly attached in the guide 41, and therefore pushes the casting 26 in a direction parallel to said rail. In other words, the edge of the car wall constituting the door opening acts as a stop to prevent the door 2 from moving parallel to the rail 4, and the rod 38 pushing the rod 9 parallel to said rail, there will be a resolved component acting on the pivot 14 pulling the edge of the door toward the rail 4, while the jaw 65 will be jammed against the rail 4, and the door accordingly will be pulled outward toward said rail 4. In actual practice, however, the casting 28 is not stationary, as above supposed, but is permitted to also slide along the rail 4, and therefore the rod support 10, as well as the rod support 9, is caused to slide along the said rail simultaneously, and to thereby change their distances apart.

A little consideration will show that in each case there will be a resolved component pulling each edge of the door bodily outward and in a direction perpendicular to the rail 4. Further, it will now be clear that both the supports 9 and 10 turn on their axes during the motion above described, and when the motion is reversed, they will turn on their axes in an opposite direction. That is to say, as will be clear from a comparison of Figs. 2 and 4, the said supports 9 and 10 oscillate in their castings 26 and 28, respectively, as well as in the upper guides 8, and that this oscillating motion produces a torque which operates the upper hinge levers 13 and 16, so that the door is really moved outward by forces ap-

plied near its four corners. The door may be moved along the said rail 4 until it contacts with the stops 5, when it will be fully opened.

It will now be clear that the pivot 37 is really a floating pivot and that the action of the lever 35 is to separate the rods 9 and 10. Further, it will be seen that this separation of said rods will cause the pins 14 and 17 to move outwardly with the door, and the surfaces 45 and 46 of the countersunk castings 15 and 18, respectively, to contact with said hinge-levers 13 and 16, thereby limiting the outward motion of the door 2, as will be clear from Fig. 4 of the drawings.

The door being opened, as above disclosed, it is evident it may be readily closed by simply pushing it along the rails 1 and 4 until it comes opposite the opening in the car wall, whereupon a reverse motion of the lever 35 will bring the parts to their closed position, as indicated in Fig. 2.

An important feature of my invention resides in the fact that the supports or rods 9 and 10 are moved in opposite directions in opening the door, and further, that the pivots 14 and 17 are countersunk in the door, to such an extent, that when the door is fully opened, the rods 9 and 10, as well as the levers 13 and 16, are so nearly in line with the door, as not to project beyond its outer surface. In other words, if the pivots 14 and 17 were not countersunk, and the rods 9 and 10 still placed within the line of the door, there would not be a sufficient inclination of the levers to close the door. Stated in another way, the rail 4 being located as is usual on the cars, the levers 13 and 16 would not, in the case supposed, be inclined as illustrated, and therefore the reverse motion of the lever 35 would not close the door. Again, by countersinking the pivots 14 and 17, the parts do not come outside of the line of the door, and the danger of being brushed off in transit is avoided. The stop surfaces 45 and 46 by limiting the outward movement of the parts also greatly aid in attaining this result.

The stops 5 are located at a height sufficient to clear the castings associated with the rod 10, and do not extend from the wall of the car a distance sufficient to contact with the said rod, as will be clear from Fig. 9. The rod 38 freely slides in the guide 40, as shown in Fig. 8, and the pin 50 for the roller 12 is provided with a head 51 which is held in position by said rod, as shown.

In the form shown in Fig. 5, the construction is the same as in the preceding figures, except the lever 35 is omitted, and there is substituted for the casting 28, a casting 55 which is or may be substantially like the casting 26, while a rod 56 is secured to the casting 26 by the means shown in Fig. 9,

and a similar rod 57 is secured to the casting 55 by a similar means. A lever 58 is pivoted to the rod 56 at 59, and to the rod 57 at 60.

It is evident that upon moving the lever 58 from its full line to its dotted line position, the castings 23 and 55, as well as the rods 9 and 10 will be caused to approach, and upon moving said lever from its dotted line to its full line position said parts will be separated. It therefore follows the hinge levers 13 and 16 being secured to said rods 9 and 10, respectively, as in Fig. 2, the car door will be closed and opened by these motions as in the forms of my invention, illustrated in Figs. 1 to 4.

The form shown in Fig. 6 is similar to the preceding forms but differs therefrom in being provided with an adjusting means 70 for regulating the length of the connecting rod 38.

It is obvious that those skilled in the art may vary the details of construction, as well as the arrangement of parts without departing from the spirit of my invention, and therefore, I do not wish to be limited to the above disclosure except as may be required by the claims.

What I claim is:—

1. In an apparatus for bodily moving a door in a direction perpendicular to its face, the combination of separated, oscillating, supporting rods for said door movable toward and from each other; castings associated with said supports; a rail on which said castings run; pivoted lever connections between said rod supports and said door; and means for changing the distance between said supports and thereby bodily moving said door in a direction perpendicular to its face, substantially as described.

2. In an apparatus for bodily moving a door in a direction perpendicular to its face, the combination of separated, oscillating rods supporting said door movable toward and from each other; castings secured to said supports; a rail on which said castings run; pivoted lever connections between said rod supports and said door; and means comprising a lever for changing the distance between said supports and thereby oscillating and moving said supports and bodily moving said door in a direction perpendicular to its face, substantially as described.

3. In an apparatus for bodily moving a door in a direction perpendicular to its face, the combination of separated, movable oscillating rods for supporting said door; pivoted lever connections between said rod supports and said door; and means comprising a lever and a sliding connecting rod for changing the distance between said supports and thereby oscillating and moving said supports and bodily moving said door in a direction perpendicular to its face, substantially as described.

4. In an apparatus for bodily moving a door in a direction perpendicular to its face, substantially as described.

5. In an apparatus for bodily moving a door in a direction perpendicular to its face, the combination of separated, movable oscillating rods; castings in which said rods fit; a supporting rail for said castings; levers rigid with said rods; pivoted connections between said levers and said door; a connecting rod between said castings; and a lever associated with said connecting rod adapted to change the distance between said castings and oscillating rods and thereby cause said door to move bodily in a direction perpendicular to its face, substantially as described.

6. In an apparatus for bodily moving a door in a direction perpendicular to its face, the combination of separated, movable, oscillating rods; castings in which said rods fit; a supporting rail for said castings; a top guide rail; sliding connections between said rods and said top guide rail; levers rigid with said rods; pivoted countersunk connections between said levers and said door; a connecting rod between said castings; and a lever associated with said connecting rod adapted to change the distance between said castings and oscillating rods and thereby cause said door to move bodily in a direction perpendicular to its face, substantially as described.

7. In an apparatus for bodily moving a door in a direction perpendicular to its face, the combination of separated, oscillating supporting rods; movable toward and from each other; castings in which said rods fit; a supporting rail for said castings; a top guide rail; connections between said rods and said top rail; levers rigid with said rods; pivoted connections comprising countersunk castings provided with stop surfaces between said levers and said door; a connecting rod between said castings; a guide for said rod and a slot associated with one of said castings; and a lever co-acting with said slot associated with said connecting rod adapted to change the distance between

115
120
125

said castings and oscillating rods and thereby cause said door to move bodily in a direction perpendicular to its face, substantially as described.

5 8. In a means for bodily moving car doors, the combination of separated independent castings, one of which is provided with a slot and a guide; an operating lever coacting with said slot; a rod connecting

said castings passing through said guide; 10 and a pivoted connection between said rod and lever, substantially as described.

In testimony whereof I affix my signature, in presence of two witnesses.
